(57) **CLAIM**

The ornamental design for a data vault, as shown and described.

DESCRIPTION

FIG. 1 is a perspective view showing my new design;

FIG. 2 is an elevational view;

FIG. 3 is a top plan view;

FIG. 4 is an elevational view;

FIG. 5 is an elevational view; and,

FIG. 6 is a bottom plan view.

The broken line drawings of an electrical connector are for illustrative purposes only and form no part of the claimed design.
